PACKAGE OF SQUARE-CUT PAPERS

David B. Dreiman, 2 Sherman Ave., White Plains, N.Y.

Filed Aug. 30, 1960, Ser. No. 61,942

Term of patent 14 years

(Cl. D58—2)

FIG. 1.

FIG. 2.

Figure 1 is a front elevational view of a package of square-cut papers, showing my new design. The rear is substantially plain except for the band across the middle; and

I claim:

The new and ornamental design for a package of square-cut papers, substantially as shown and described.
